UNITED STATES PATENT OFFICE.

WILLIAM R. MORRIS, OF PINE BLUFF, ARKANSAS.

SAW-SHARPENING MACHINE.

SPECIFICATION forming part of Letters Patent No. 622,964, dated April 11, 1899.

Application filed April 7, 1898. Serial No. 676,817. (No model.)

To all whom it may concern:

Be it known that I, WILLIAM R. MORRIS, a citizen of the United States, residing at Pine Bluff, in the county of Jefferson and State 5 of Arkansas, have invented certain new and useful Improvements in Saw-Sharpening Machines; and I do declare the following to be a full, clear, and exact description of the invention, such as will enable others skilled in 10 the art to which it appertains to make and use the same.

The invention has relation to saw-sharpening machines and is particularly designed for sharpening cotton-gin saws.

15 Among the various objects of the invention is to provide a simple and inexpensive machine of this character with numerous adjustments for accomplishing the desired end.

With this object in view the invention consists in certain features of construction and 20 combinations of parts, which will be hereinafter fully described and claimed.

In the accompanying drawings, Figure 1 is a 25 perspective view of my improved machine, showing it in the act of sharpening a cotton-gin saw. Fig. 2 is a top plan view. Fig. 3 is a side elevation. Fig. 4 is a rear end view; and Fig. 5 is a detail perspective view of the 30 end of one of the file-bars, showing the manner of attaching the files thereto.

In said drawings, A denotes an upright frame consisting of the sill B, the outer vertical standard C, and the inner vertical standards D, connected at their upper ends by 35 cross-bars E.

18 denotes a drive-shaft journaled in bearings secured to several of the standards and provided with a drive-gear F.

G denotes a shaft journaled to boxes secured to the inner standards D and provided with a fly-wheel H and a pinion I, in mesh 40 with the drive-gear F.

21 denotes bars having their inner ends secured to the outer standards C. These bars 45 converge to a point 17' and then are formed with parallel arms 17², which are adapted to rest upon the arbor of the gin-saws and support the machine when in the act of sharpening the saws while they are in the gin-stand.

50 7 denotes a block arranged between the converging sides of the bars 21 and pivoted

thereto by pivot-bolts 7'. One surface of this block, as at 7², is above the other surface at 7³ for a purpose hereinafter to appear. This block has an arm 15, that projects rearwardly 55 and is provided with a slot 15', through which projects an adjusting-screw 15², swiveled in the sill B of the frame. 15³ denotes jam-nuts upon said screw. When it is desired to tilt the block, these jam-nuts are loosened, and 60 the slotted end of the arm 15 is raised or lowered, as desired, and the nuts are then screwed tight against the end of the bar 15 to hold it and the block to which it is attached in desired adjustment. 3 denotes boxes located 65 upon said surfaces 7² and 7³. Each box is pivoted to the slotted plate 6, which is adjustably secured to the surfaces 7² and 7³ of the block by bolts 6'. Near the rear ends of the box and adjustably secured to the surfaces 7² and 7³ of the block are stop-lugs 55, that limit the inward movement of the boxes. 2 denotes curved springs each having one end secured to the block and having its other end bearing against the boxes. 2' denotes a stud 70 projecting up from the surfaces 7² and 7³ of the block and provided with a screw-threaded aperture to receive the set-screws 2^a, which are adapted to be adjusted for a purpose hereinafter to appear. Arranged within these 75 boxes are reciprocating file-bars 4, having secured to their outer ends files 4'. These files are held to the bars 4 by a bolt 4^a and a notched nut 4^b, the notch in said nut engaging the angle of the file-bar. These file-bars 80 are alternately reciprocated by cranks 4^d, secured on the shaft G and connected to the file-bars by links G'.

13 denotes a bracket secured to the side bars 21 and projecting under the block 7 and 90 formed with a bearing-loop 13', provided with a horizontal row of holes 13².

12 denotes an eccentric-pitman strapped to an eccentric 12', secured to the shaft 18. The lower end of this pitman is provided with a 95 vertical row of holes and is adjustably connected to a lever 11 by bolts 11'. This lever is adjustably pivoted by a bolt 11² in the bearing-loop 13' and has adjustably pivoted to its outer end a dog 11³, which is adapted to engage the teeth of the saw and move the saw tooth by tooth as it is being sharpened by the 100

files, the construction and movement being such that each is filed on opposite sides before the saw is rotated the distance of one tooth.

5 8 denotes a cross-piece secured to the bars 17 and provided at its ends with slots 8'. 9 denotes arms which are longitudinally adjustable in said slots by means of the bolts 9'. These arms at their outer ends are forked and 10 adapted to engage the arbor of the saw and hold the machine in proper relation thereto.

10 15 19 denotes an auxiliary supporting forked arm which is also secured to the bar 8, and 19 denotes a flat spring secured to the under side of the block 7 and bearing down upon the upper edge of the free end of the lever 11. This spring serves to prevent the lever being thrown too far forward and takes up lost motion in the parts.

20 From the foregoing description, taken in connection with the accompanying drawings, the construction of the machine will be readily understood without requiring a further explanation.

25 By means of the holes in the lower end of the eccentric-pitman 12 and those in the loop 13' of the bracket 13 the feed can be regulated to suit saws having long or short teeth. The lugs 9 are made adjustable, so as to adapt 30 the machine to large or small saws.

When it is desired to cut long teeth, the boxes 3 are moved inward by adjusting the stops 5 and bolts 6. The springs 2 are then adjusted by means of their set-screws to permit of the desired yielding movement of the boxes. To cut short teeth, the boxes are moved outward and the springs correspondingly adjusted.

35 The inclination of the file-bars 4 gives the proper pressure to the files as they make their strokes on the saw and causes the boxes 3 to oscillate against the springs 2. The set-screw

and springs regulate the pressure of the files against the saw.

By pivoting the block 7 to the bars 21 and 45 providing suitable adjustment for tilting the block I am enabled to secure the proper angle for the files to regulate them to the saw-teeth. This may be done by raising or lowering the arm 15.

50 Although I have specifically described the construction and relative arrangement of the several elements of my invention, I do not desire to be confined to the same, as such changes or modifications may be made as 55 clearly fall within the scope of my invention without departing from the spirit thereof.

Having thus described my invention, what I claim, and desire to secure by Letters Patent, is—

60 In a machine of the character described, the combination with the main frame provided with bars projecting outwardly therefrom, a block pivoted between said bars, plates 6 adjustably secured to the block, boxes 65 pivoted to the plates, springs engaging said boxes, means for adjusting the tension of said springs, stop-plates 5 secured to said block and engaging said boxes at the rear of their pivotal connection with the block, reciprocating file-bars mounted in said boxes, 70 files secured to their outer ends and crossing one another, mechanism for feeding the saw to be operated upon, and mechanism for reciprocating the file-bars, substantially as set 75 forth.

In testimony whereof I have hereunto set my hand in presence of two subscribing witnesses.

WILLIAM R. MORRIS.
